United States Patent [19]
Gill

[11] Des. 269,063
[45]  May 24, 1983

[54] COMBINED RECESSABLE LOCK
CASEMENT HASP AND STAPLE

[76] Inventor: Robert Gill, 401 Liberty Blvd.,
Phillipsburg, N.J. 08865

[] Term: 14 Years

[21] Appl. No.: 217,590

[22] Filed: Dec. 18, 1980

[51] Int. Cl. .... D8—07

[52] U.S. Cl. D8/343; D8/345

[58] Field of Search D8/345, 346, 331, 343,
D8/344; 292/341.14, 281, 285; 70/52, 54, 56

[56] References Cited

U.S. PATENT DOCUMENTS

D. 153,341	4/1949	Ferry	D8/331
2,798,753	7/1957	Wade	292/346 X
3,736,016	5/1973	Garvey et al.	292/281
4,079,974	3/1978	Roper	292/281
4,106,315	8/1978	Dohanyos	292/281 X
4,331,356	5/1982	Noel	292/281

Primary Examiner—A. Hugo Word

Attorney, Agent, or Firm—Ruth Moyerman

[57] CLAIM

The ornamental design for a combined recessable lock casement hasp and staple, as shown.

DESCRIPTION

FIG. 1 illustrates a front perspective of this invention shown without a lid.

FIG. 2 illustrates a rear perspective of the view shown in FIG. 1.

U.S. Patent

May 24, 1983

Des. 269,063

FIG. 1

FIG. 2